MEAT CHOPPER KNIFE

Clarence R. Williams, Brooklyn, N. Y., assignor to Atlantic Service Company, Inc., Brooklyn, N. Y., a corporation of New York

Application December 28, 1951, Serial No. 17,840

Term of patent 14 years

(Cl. D89—1)

To all whom it may concern:

Be it known that I, Clarence R. Williams, a citizen of the United States of America, and a resident of Brooklyn, New York, have invented a new, original, and ornamental design for a Meat Chopper Knife, of which the following is a specification, reference being had to the accompanying drawing, forming a part hereof.

I claim:

The ornamental design for a meat chopper knife, substantially as shown.

CLARENCE R. WILLIAMS.
